UNITED STATES PATENT OFFICE.

JAMES A. NORTON, OF WILKESBARRE, PENNSYLVANIA, ASSIGNOR
OF ONE-HALF TO WILLIAM L. RAEDER, OF WILKESBARRE, PENNSYLVANIA.

TROLLEY.

SPECIFICATION forming part of Letters Patent No. 783,458, dated February 28, 1905.

Application filed December 23, 1904. Serial No. 238,080.

To all whom it may concern:

Be it known that I, JAMES A. NORTON, a citizen of the United States, residing at Wilkesbarre, Luzerne county, State of Pennsylvania, have invented certain new and useful Improvements in Trolleys, of which the following is a specification.

The present invention relates to improvements in trolleys, and has for its object to provide a construction in which any looseness due to wearing of the parts may be compensated, so that the wheel may run freely and evenly and without unnecessary noise or vibration.

A further object is to provide a construction which will not require frequent attention to maintain proper lubrication of the moving parts and to provide for readily removing and replacing the wheel of the trolley.

Referring to the accompanying drawings, Figure 1 is a sectional view of a trolley-head constructed in accordance with this invention. Fig. 2 is a view taken on the line 2 2 of Fig. 1 looking in the direction of the arrow. Fig. 3 is an elevation of one of the hub-sections of the wheel. Fig. 4 is a detail view of the means for connecting the members of the harp.

Referring to the drawings, 1 designates the pole or staff of a trolley, which may be of any suitable construction and which is provided at its upper end with a harp or wheel support consisting of two members 2 3, the latter being pivotally connected with the former at a point 4, whereby it may be swung laterally and downwardly to permit removal of the wheel-center 5. The latter is supported by and between two hub-sections 6, which are mounted to turn about suitable bearings 7, attached to the sides of the harp. As shown, each of said hub-sections is provided at its center with an inwardly-extending boss 8, having a flattened face or surface 9, the wheel-center 5 having suitable recesses formed in its opposite faces to receive such bosses, whereby the said center piece and hubs are connected to rotate together. Each of the hub-sections is provided with an outwardly-extending peripheral flange 10, and the space inclosed by such flange is divided by partitions

or webs 11 to provide a plurality of lubricant-receptacles 12 and intermediate radially-extending passages or guides for adjustable bearing-blocks 13. In the embodiment of the invention shown in the drawings each of the hub-sections is provided with three of such lubricant-compartments and three of the bearing-blocks, the latter being adjustable radially of the hub by suitable screws 14. Preferably each of said blocks consists of a metal body having its inner face made concave to conform to the surface of the bearing 7 on which it is mounted, and each of said blocks is shown as having a plurality of grooves or recesses at its inner end, in which are arranged suitable bodies 15, of rawhide or similar material. Each of the lubricant-chambers 12 communicates with the passage in the hub through which the bearing 7 extends by means of openings 17, whereby as the wheel revolves lubricant is freely supplied from such chambers to the bearings. By means of the adjusting-screws 14 the blocks 13 are maintained in contact with the journal 7, and any wear consequent on use can be compensated for by adjusting said screws.

Means are provided for detachably holding the swinging member 3 of the harp in the position shown in Fig. 1. Various means may be employed for this purpose, that illustrated being a transverse bar 20, extending through suitable apertures in the harp members and secured in position by cotter-pins 21 22. By removing either pin 21 22 the bar 20 can be withdrawn from engagement with the harp and the swinging side thereof readily moved outwardly. In such outward movement the hub-section 6 adjacent said swinging side of the harp will be withdrawn from the other parts of the wheel, said hub-section being supported on the bearing 7, as will be evident from an examination of Fig. 1. The wheel-center can then be readily drawn from the other hub-section and a new center substituted, if desired. To remove either of the hub-sections after the parts have been disengaged as above described, the adjusting-screws 14 are withdrawn, so that the blocks 13 are not

pressed closely against the bearing 7, and the hub-section can then be readily withdrawn from the bearing.

Having thus described the invention, what I claim is-

- 5 1. In a trolley, the combination with a harp or wheel-fork, having a rigid side member and a swinging side member, of a bearing rigidly connected with and extending inwardly from each side of the harp, a wheel comprising a sectional hub and a center detachably connected to said hub, the hub-sections being mounted to rotate on said bearings and each provided with a plurality of 10 radially-extending passages, bearing-blocks arranged within said passages, means for adjusting said blocks toward the axis of the wheel, and means for detachably connecting the members of the harp.
- 15 2. In a trolley, the combination with a harp or wheel-fork, having a rigid side member and a swinging side member, of a bearing rigidly connected with and extending inwardly from each side of the harp, a wheel comprising a sectional hub and a center detachably connected to said hub, the hub-sections being mounted to rotate on said bearings and each provided with a plurality of 20 radially-extending passages, bearing-blocks arranged within said passages, adjusting-screws mounted in bearings at the outer ends of said radial passages in the hub and adapted to move said blocks toward the wheel-axis, and means for detachably connecting the 25 members of the harp.
- 30 3. In a trolley, the combination with a harp or wheel-fork, having a rigid side member and a swinging side member, of a bearing attached to and extending inwardly from each side of the harp, a wheel comprising two hub-disks adapted to rotate on said bearings and a center detachably connected to said-disks to rotate therewith, each of said hub-disks having formed therein a plurality of radially-extending 35 passages, bearing-blocks fitted in said
- 40 passages and adapted to be pressed against the bearing on which the disk rotates, means for applying lubricant to the bearing at points between the said radial passages in the hub-disks, and means for detachably connecting the members of the harp.
- 45 4. In a trolley, the combination with a harp or wheel-fork, having a rigid side member and a swinging side member, of a bearing attached to and extending inwardly from each side of the hub, a wheel-hub mounted to rotate on said bearings, said hub having about each bearing a plurality of radially-extending 50 passages and intermediate lubricant-receptacles, the lubricant-receptacles having ducts opening through the inner surface of the hub, bearing-blocks fitted in said radial passages, means for adjusting said blocks toward the bearing on which the hub-disk is mounted, a wheel adapted to be detachably engaged with 55 said hub to rotate therewith, and means for detachably connecting the members of the harp.
5. In a trolley, the combination with a harp or wheel-fork, having a rigid side member and a swinging side member, of a bearing attached to and extending inwardly from each side of the harp, a sectional wheel-hub having a section mounted to rotate on each of said bearings, and having a lubricant-receptacle formed in each section and communicating 60 with the space surrounding the bearing on which the hub-section is mounted, means adjustable radially of the hub for maintaining it in proper position on said bearings, a wheel adapted to be detachably engaged with the 65 hub to rotate therewith, and means for detachably connecting the members of the harp.
- 70 In testimony whereof I have signed my name to this specification in the presence of two subscribing witnesses.
- 75 JAMES A. NORTON.
